DEVICE FOR HAIR WAVING

Charles P. Simas, Taunton, Mass.

Application May 14, 1941, Serial No. 393,375

2 Claims. (Cl. 132—36)

This invention relates to a device used in hair waving, and more especially to one that is used to apply heat to the hair.

The principal object of my invention is to provide a device that will serve to conduct a heating medium such as steam to the hair waving clip and direct it towards the hair being curled. Another object is to provide said device with anchoring means that will hold it in a fixed operative position.

I am well aware that steam has been used to set curls in hair waving; but heretofore its use has required a special hair waving clip or the operator has had to hold the steam supply tube in association with the usual hair waving clip with the consequence that, because of this bother, steam has not commonly been used, but chemical heating pads have although they are more expensive and more unsatisfactory in some ways than steam. My invention enables the operator to supply with steam, or a similar heating medium, the usual hair waving clip while it encloses the hair being waved without requiring the presence of the operator too. This has been accomplished by a simple device that holds the steam supply conduit in a predetermined position.

The foregoing and other objects which will appear as the nature of the invention is better understood, may be accomplished by a construction, combination and arrangement of parts such as is disclosed by the drawing and specification. The nature of the invention is such as to render it susceptible to various changes and modifications, and, therefore, I am not to be limited to said disclosure; but am entitled to all such changes therefrom as fall within the scope of my claims.

In the drawing:

Figure 1 is a front elevational view of my device in operation.

Figure 2 is a plan view of my device.

Figure 3 is an enlarged side elevational view of my device, partly in section.

As illustrated, I have shown a source of steam supply having an electrical heating element 12 supported by a base 13 on which also rests a container 14 to hold the water that is converted into steam. Said container 14 has an outlet pipe 15 to which is attached a steam supply tube 17.

My device is attachable to and communicable with said steam supply tube and consists of a steam delivery conduct 21 that may be stiff and made of metal with a right angle intermediate bend and preferably has an extension or vizor

portion 22 at its outside end that preferably slants inwardly.

One end of said conduit 21 is adapted to extend into said supply tube 17 so that steam passes through said conduit 21 and out through the open end. Said extension portion 22 directs the steam away from it and inward, of course, and thus controls the direction of the steam to that extent.

10 Mounted on said supply conduit 21 is a gripping member 19 by which my device is grasped and held. It is preferably made of wood or other poor heat conducting material such as fiber. Fastened to said supply conduit 21 is an anchoring means adapted to hold said supply conduit 21 in a predetermined position, having a connecting means such as a cord 23 that is preferably fairly stiff but flexible. A short length of cloth covered wire will serve the purpose, although a chain or cord of resistably bendable metal could be used. It has a spring clamp member 24 of well known construction fastened to it at one end. The other end is attached to a boss 25 which said tube 21 has or it can be wound around or otherwise fastened to said tube.

In curling hair as in permanent waving, a hair waving clip 26 of well known construction is commonly used which has a pair of handles 27 which operate a pair of jaws 28. Said clip 26 substantially covers a curler 30 around which the hair H is curled.

In using my device, as illustrated in Figure 1 of the drawing, one end of said conduit 21 is 35 in communication with said steam supply tube 17 while the other (outlet) end is inserted into the hair waving clip 26 at either end between the latter's said jaws 28 with the extension or vizor portion 22 preferably in upper position so that the steam will be directed downwardly towards the hair. At the opposite end of said clip 26 some cotton 29 or the like is stuffed into it to help retain the steam. Merely inserting said conduit 21 in said clip 26 will not hold it there, 40 and it would require a person to stand there and hold it were it not for my anchoring means whose clamping member 24 is clamped onto said hair waving clip 26 thereby anchoring said conduit 21 in any predetermined position within said hair waving clip 26, that is desired.

What I claim is:

1. A steam applicator for use in hair waving comprising a flexible steam conduit portion, a rigid conduit portion connected therewith having an intermediate rectangular bend and

equipped with a non-heat conductive hand piece, the extremity of said rigid portion adapted to be inserted within a hair waving clip, and a clasp having a flexible element secured to said rigid portion with a capability of adapting movement with respect thereto and adapted to be engaged with a hair waving clip to hold said rigid conduit portion in place within said clip.

2. A steam applicator for use in hair waving comprising a steam conduit with a rigid terminal

portion and having a right angle intermediate bend, a clasp having a flexible element secured to said portion with a capability of adapting movement with respect thereto, and adapted to be engaged with a hair waving clip to hold the extremity of said conduit portion in place within the clip, and a deflector at the extremity of said conduit portion adapted to direct the steam inward upon the hair held by said clip.

CHARLES P. SIMAS.
